S. B. BEDINGER.

BED ATTACHMENT.

APPLICATION FILED JUNE 1, 1920.

1,368,600.

Patented Feb. 15, 1921.

UNITED STATES PATENT OFFICE.

SINGLETON B. BEDINGER, OF TERRELL, TEXAS, ASSIGNOR OF ONE-HALF TO L. E. GRIFFITH, JR., OF KAUFMAN COUNTY, TEXAS.

BED ATTACHMENT.

1,368,600.

Specification of Letters Patent. Patented Feb. 15, 1921.

Application filed June 1, 1920. Serial No. 385,535.

To all whom it may concern:

Be it known that I, SINGLETON B. BEDINGER, citizen of the United States, residing at Terrell, in the county of Kaufman and State of Texas, have invented certain new and useful Improvements in Bed Attachments, of which the following is a specification.

This invention relates to new and useful 10 improvements in bed attachments.

An important feature of the invention is an attachment which may be stored under an ordinary bed in such a manner as not to be unsightly and yet in convenient position 15 to be readily used as an additional sleeping means.

In carrying out the invention supporting members are arranged at each end of an ordinary bedstead and hangers are arranged so as to slide longitudinally of the members and transversely of the bed. The hangers support the inner ends of an auxiliary bed frame. This frame has its outer 20 end supported on legs which are provided with casters, said legs being adapted to be folded up against the frame when the bed attachment is slid inward and is not in use. A supporting member or hook is provided 25 on the outer ends of the frame and may be engaged with one of the side rails to support the frame when the same is slid under the bed. Various other novel features will be 30 hereinafter more particularly pointed out.

The invention will be more readily understood from a reading of the following 35 specification and by reference to the accompanying drawings, in which an example of the invention is shown, and wherein:

Figure 1 is a perspective view of a bed 40 equipped with an attachment in accordance with my invention,

Fig. 2 is a sectional detail of one of the hangers,

Fig. 3 is a side elevation of the same,

Fig. 4 is a detail of the hanger,

Fig. 5 is a detail of one of the adjustable parts of the hanger,

Fig. 6 is a detail showing one of the folding legs of the bed frame,

Fig. 7 is a perspective view of the supporting hook, and

Fig. 8 is a perspective view of an auxiliary rail for a short length frame.

In the drawings the numeral 10 designates the head section of an ordinary bed

and 11 the foot section, said sections being connected by the usual side rails 12. Between the posts of the said sections I mount tracks or supporting members 13 which may by suitably attached to said sections, either 60 permanently or temporarily. The tracks 13 are preferably angular in cross section, each having a flat side uppermost.

The attachment includes an extendable frame which comprises a head bar 14, a foot 65 bar 15 and side bars 16 and 17 respectively. These bars are preferably formed of angle iron and are disposed, the head and foot bars with their flanges uppermost and the side bars with their flanges depending 70 as clearly shown in the drawings. The bars are suitably fastened together at the corners of the frame so as to form the latter. At the inner edge of the head and foot bars hangers 18 are provided. Each hanger has 75 a laterally directed foot 19 which is fastened within the angle of the bar. A vertically adjustable element 20 is provided with a longitudinal or vertical slot 21 receiving a reduced and upwardly bent lug 22 carried 80 by the main upright of the hanger. Each upright is provided with a plurality of holes 22' receiving a bolt 23 which passes through the element 20 and receives a wing nut 24. By engaging the bolts 23 in different holes 85 the length of the hangers may be varied.

Each element 20 includes an overhanging bracket 25 in which a horizontal roller 26 is journaled. The bracket engages over the tracks 13 so that the hangers are supported by the tracks and the rollers will travel thereon. Each bracket has a keeper 27 extending from its end down to the element 20 below the slot 21 and under its respective track 13. It will be seen that the 90 hangers support the inner sides of the extension frame and the latter may be pulled outward or pushed inward readily, the rollers 26 traveling on the track 13.

At each end of the down turned flange of 100 the side bar 17 is pivoted a leg 28. These legs are preferably formed of angle iron and each carries a caster 29 at its lower end, which rests on the floor and supports the outer side of the frame when the latter is 105 being used. Each leg may be folded up against the under side of the bar 17 and within the angle of the same as is indicated in dotted lines in Fig. 6. At the central portion of the side bar 17 a hinged plate 30 110

is pivoted so as to be partially rotated. A hook 31 is hinged to the plate and may be folded down flat on the rail as is shown in Fig. 1 or swung upward and turned at right angles as is shown in Fig. 7. The hook 31 has a hand grip 32 secured thereto so as to be more readily grasped. When the frame is pushed inward the hook has its upper end engaged over the side rails 12 of the bed thus supporting the frame and permitting the leg to be swung upward thus removing all depending parts which might interfere with sweeping under the bed and which would be unsightly.

15 When it is desired to use the bed attachment the hook 31 is disengaged given a quarter turn and laid down flat on the bar 17 as is shown in Fig. 1. The legs 28 are swung downward and the frame pulled outward to the position shown in Fig. 1. Suitable springs and mattress (not shown) are placed on the frame and a bed made up in the usual way. The advantages of such an arrangement are obvious and the simplicity of the device is apparent.

20 Where a short length attachment is desired the foot track 13 is omitted and an auxiliary track 33, as is shown in Fig. 8 is used. This track 33 has upright brackets 34 which may be fastened to the side rails 12. The foot hanger is engaged over this track and a shorter frame used.

25 What I claim is:

1. In a bed attachment; a pair of trans-
30 verse track members for attachment to a
bed; a permanently assembled frame; ver-
tically adjustable hangers secured to the
ends of the frame near its inner side, each
hanger comprising a lower strip provided
40 at its upper end with a laterally extending
tongue and a plurality of spaced apertures
beneath the tongue, an upper strip slidably
engaging the lower strip and having a lon-
gitudinal opening to receive the tongue and
45 an aperture beneath the opening, a clamp-
ing bolt passed through the aperture of
the upper strip and adapted for insertion in
selected aperture in the lower strip, said
upper strip having an inverted U-shaped
50 overhanging bracket, to extend over the
track members, a roller carried by the
bracket and engaging the track member,
and a diagonal keeper secured to the free
end of the approximately U-shaped bracket

55 and extending downwardly for connection
with the upper strip at a point beneath the
longitudinal opening therein; and legs se-
cured to said frame and its ends and near
its outer side.

2. In a bed attachment; a pair of trans-
60 verse track members for attachment to a
bed; a substantially rigid frame; vertically
adjustable hangers secured to the ends of
the frame near its inner side, each hanger
65 comprising a lower strip provided at its
upper end with a laterally extending
tongue and a plurality of spaced apertures
beneath the tongue, an upper strip slidably
engaging the lower strip and having a lon-
70 gitudinal opening to receive the tongue and
having an aperture beneath said opening, a
clamping bolt passed through the aperture
of the upper strip and adapted for inser-
tion in a selected aperture in the lower strip,
75 said upper strip having an inverted U-
shaped overhanging bracket to extend over
the track member, and a roller carried by
the bracket and engaging the track mem-
ber; legs pivotally connected with the ends
80 of the frame near its outer side and adapt-
ed to be folded upwardly with relation
thereto; and a hook secured to the outer
side of the frame and adapted to engage
over the longitudinal rail of the bed.

3. In a bed attachment, a pair of trans-
85 verse track members adapted for connec-
tion with a bed, a frame for movement be-
neath the bed and track members, hanger
devices secured to the frame near its ends
and inner side and engaging the track
90 members, legs pivotally connected with the
frame near its ends and outer side and
adapted to be folded upwardly with relation
thereto, a strip pivotally connected with the
upper face of the outer side of the 95
frame and adapted to be turned in a sub-
stantially horizontal plane, and a second
strip having a hinged connection with the
first named strip and having its free end
bent into a hook to engage over the longi-
100 tudinal rail of the bed, said strips being
adapted to be disposed in end to end rela-
tion longitudinally upon said upper face
and to be also arranged transversely of the
face with one strip disposed at a right an-
gle to the other.

In testimony whereof I affix my signature.
SINGLETON B. BEDINGER.
